multiple grinding machine, the invention being a modification of the machine disclosed in my prior patent, U. S. Patent No. 1,497,574, entitled "Internal Grinding Machine", issued to me on June 12, 1924, and which is herein referred to as the "McDonough machine". The present invention is a modification of the machine disclosed in my prior patent, the improvement being in the manner of controlling the grinding units.

UNITED STATES PATENT OFFICE

CLIFFORD T. RAULE, OF BROOKLINE, PENNSYLVANIA

INTERNAL GRINDER CONTROL

Application filed March 1, 1929. Serial No. 843,801.

My invention relates to multiple grinding machines in which duplicate grinding units are mounted at spaced intervals around a turn-table and the grinding operation is completed at each unit during a single rotation of the table, work pieces being loaded into the units as they pass a loading position and ground to size before they reach an unloading position adjacent and somewhat back of the loading position, the invention having particular reference to a safety device.

A purpose of my invention is to stop the rotary movement of the table if a grinding unit reaches a designated point of its orbit without having the wheel withdrawn from the work. Usually the designated point is one a little before unloading position. I mount a shift lever, adapted to stop the turn-table, so as to be operated by any grinding unit reaching the designated point without having made a determinative movement characteristic of having completed its grinding, the normal determinative movements at the units before the units reach the shift lever being necessary to avoid stoppages of the turn-table as the units reach the designated point.

I prefer to make the withdrawal of the wheel from the work the characteristic determinative movement and mount downwardly pressing pins upon the individual wheel units to engage and operate the shift device when the units reach the designated point if the normal withdrawal movement has not been made.

Further purposes will appear in the specification and in the claims.

I have elected to show one only of the many forms of my invention, selecting a form that is practical and efficient in operation and which well illustrates the principles involved.

Figure 1 is a top plan view of a multiple grinding machine structure adapted to embody my invention. The view is partially diagrammatic with many parts removed for greater simplicity and clearness, the type of machine selected for illustration being that disclosed in McDonough Patent No. 1,497,574 entitled "Internal grinding machine".

Figure 2 is a fragmentary left-end elevation of Figure 1.

Figure 3 is a fragmentary elevation, part section, showing a grinding unit in position to effect a shut down of the turn-table.

Figure 3a is a view corresponding to Figure 3, showing the parts in different position, that in which there will be no shut down.

Like numerals refer to like parts in all figures.

Describing in illustration and not in limitation and referring to the figures:

Figure 1 is intended for a conventional illustration of any turn-table to which my invention is adapted to be applied, but in order to avoid the necessity for describing in detail features that do not in themselves directly relate to my invention I have made Figure 1 in general to accord with the turn-table disclosed in McDonough patent above referred to.

The turn-table 10 is rotatably mounted upon stationary supporting structure 11, lateral brackets 12 of the table carrying wheels 13 which roll round upon suitable circumferential track 14 of the supporting structure.

Grinding units are mounted at spaced intervals around the table, each unit comprising a work-holder 15 and a grinding wheel unit 16 (only one of each shown in Figure 1).

The wheel units with wheels rapidly revolving, traverse at variant heights in vertical heights in vertical guides 17 of the turn-table which carries the work-holders beneath the respective wheel units, the wheel units being adapted to traverse grind work pieces 18 in the respective work-holders.

The turn-table is driven by belt 19, pulley 20 shaft 21 and a friction drive disc 22.

The shaft 21 is journaled in suitable bearings 23 at the side of the supporting structure and the periphery of the disc 22 engages the face of a friction wheel 24 that is adapted to rotate the turn-table by mechanism not shown and irrelevant to the present invention. The disc 22 is illustrated as adjustable along its shaft at 25 to vary the rate of rotation of the friction wheel 24.

The work-holder and wheel units may be operatively connected to mechanisms driven by the friction wheel 24—or otherwise as desired, but the drive of the turn-table is desirably independent of that of the wheel and work-holder units and such as to permit stopping rotation of the turn-table without interrupting traverse grinding. Most of the mechanism shown in Figure 1 is described 10 in detail in the McDonough patent referred to.

Work pieces are fed into the successive work-holders by any suitable loader 26 that remains at one position, feeds the work pieces 15 into the holders as they pass and that preferably operates automatically.

The pieces are unloaded after having been ground to size and having made almost complete circuit of the machine, by discharge 20 mechanism 27 that preferably operates automatically and is placed some little distance before the loader 26.

Both the loading and unloading mechanisms may be of any suitable types, as for 25 example such as are already described and claimed by me in one or more copending applications, and are illustrated here diagrammatically, the actual mechanisms being irrelevant to the present invention.

30 The work-holders are loaded with new pieces as they pass the loader 26, while the wheel units are suitably raised above the work-holders (Figure 3a).

After a work-holder is loaded at 26, the 35 wheel unit moves down to grinding position and traverse grinding begins and continues with a gradual feed between the work and wheel units until the piece is ground to size as determined by a suitable gauge or otherwise, irrelevant to the present invention, the 40 wheel units moving up out of the way when the pieces are ground to size.

Normally traverse grinding is completed and the grinding wheels have moved upwardly out of the way of unloading and loading by the time the units reach a designated point.

It may happen that the grinding operation has not been completed by the time the 50 unit reaches the designated point, beyond which it is deemed unsafe for traverse grinding to continue, or that the wheel unit has not yet risen by the time the designated point is reached so that it is in the way of unloading and loading mechanisms, and my invention aims to stop the rotation of the turn-table in this event, preferably without interfering with the operation of the grinding units mounted on the turn-table, and with 55 automatic resumption of the rotation of the turn-table when the grinding unit at the designated point has completed its grinding and the wheel unit has risen out of the way.

60 In the illustration I have mounted a rod 28 upon each wheel unit in position to en-

gage an arm 29 of the shift mechanism when the unit reaches the designated point in order to stop the rotation of the turn-table, with or without stoppage of the operation of the grinding units, if the wheel unit is then still 70 in position for traverse grinding.

The rod 28 is mounted to vertically slide in supporting bearings 30 and 31 at the ends of arms from the spindle of the grinding wheel and may be spring-pressed downwardly at 32 so as to maintain continual contact at 33 with the top of the work piece or with the upper end of the chuck, as long as the wheel unit is in position for traverse grinding, the wheel unit traversing up and down 80 and the rod remaining vertically stationary, supported by the top of the work piece or top of the work-holder in a position to engage the shift mechanism.

85 Optionally the spring 32 may be omitted, the weight of the rod holding it down upon the top of the work piece while the wheel and the bearings of the rod move up and down.

The rod engages the shift lever and stops 90 the rotation of the turn-table only when the wheel unit is in its low position, that for traverse grinding and normally the wheel unit when it reaches the designated point is raised sufficient to clear the shift lever, as illustrated in Figure 3a, the rod then missing the shift lever and not affecting the rotation of the turn-table.

95 The shift lever is an arm from a rocker shaft 34 journaled in bearings 35 and 36 and carrying at its lower end an arm 37 adapted to position the driving belt 19 upon either the drive pulley 20 or an adjacent idler pulley 38.

100 The arm 37 is connected by link 39 to a belt slide 40 mounted slidably upon a guide rod 41, and a spring 42 stretched between the end of the arm 37 and the supporting structure of the machine, automatically returns the shift mechanism to its position for 105 operating the machine when the vertical rod 28 moves up and releases the arm 29 of the shift mechanism.

110 In operation the belt is shifted by engagement between the rod on the wheel unit and the arm 29 of the shift mechanism to stop rotation of the turn-table whenever a unit reaches the designated point before its traverse grinding has ceased, and unless the wheel unit has moved up into its raised position. Preferably in this event traverse grinding continues after the turn-table stops until the work piece comes to size after which the wheel unit rises which permits the shift lever to spring back and start the turn-table. 115

120 It will be evident that the rod 28 performs an exploring function, since it determines whether or not the grinding wheel is in contact with the work. In some of the claims 130

I have referred to means of this character as exploring means.

In view of my invention and disclosure variations and modifications to meet individual whim or particular need will doubtless become evident to others skilled in the art, to obtain all or part of the benefits of my invention without copying the structure shown, and I, therefore, claim all such in so far as they fall within the reasonable spirit and scope of my invention.

Having thus described my invention, what I claim as new and desire to secure by Letters Patent is:—

15. 1. A multiple internal grinding machine having duplicate grinding units mounted at spaced intervals around a turn-table, each unit comprising a work-holder, a grinding wheel, driving means for the same, and means for applying the wheel to or removing it from the work, and in which the grinding operation is completed at each unit during a single rotation of the table, work-pieces being loaded into the units as they pass a loading position and ground to size before they reach an unloading position, in combination with a mechanical shut down for the turn-table to disconnect power driving application to the turn-table operative whenever a grinding unit reaches any designated angular turn-table position on the machine while the grinding wheel of that unit is applied to the work.
20. 2. In a multiple grinding machine, a turn-table, duplicate grinding units, each comprising a grinding wheel, means for applying the wheel to or removing it from the work, and a work-holder, mounted at spaced intervals therearound and adapted to complete the grinding operation at each unit while the unit is making a single rotation of the turn-table, in combination with a device adapted to stop the rotation of the turn-table as each unit reaches a designated point of the machine if the grinding wheel and work-holder parts of the grinding unit are relatively positioned for traverse grinding and to avoid stoppage of the turn-table if the grinding wheel is raised out of grinding position when the unit reaches said designated position.
25. 3. In a multiple grinding machine, a turn-table, duplicate grinding units, each comprising a grinding wheel, means for applying the wheel to or removing it from the work, and a work-holder, mounted at spaced intervals therearound and adapted to complete the grinding operation at each unit while the unit is making a single rotation of the turn-table, in combination with a device for automatically stopping the movement of the turn-table as each unit reaches a designated point, and means for disconnecting the device for automatically stopping the turn-table by a determinative movement of the grinding

unit characteristic of removal of the grinding wheel from the work.

4. In a multiple grinding machine, a turn-table, duplicate grinding units, each comprising a grinding wheel, means for applying the wheel to or removing it from the work, and a work-holder, mounted at spaced intervals therearound and adapted to complete the grinding operation at each unit while the unit is making a single rotation of the turn-table, in combination with shift mechanism adapted to stop the rotary movement of the turn-table, an arm mounted on each grinding unit adapted to engage and operate the mechanism when the unit reaches a designated point of the machine if the grinding wheel and work-holder parts of the unit are still relatively positioned for grinding and to miss the mechanism if the parts of the unit are relatively positioned for unloading the

5. In a multiple grinding machine, a plurality of grinding units each consisting of a grinding wheel, a bearing support thereof, means for driving the wheel within its bearing support, a work-holder, and means for moving the bearing support in a direction axial of the wheel for applying the wheel to or removing it from contact with the work in the work-holder, means for progressing the grinding units along a path, means for starting and stopping the progression, and exploring means responsive to the vertical position of the bearing support at a definite position of the wheel adapted to stop the progression of the grinding units during delay in completion of a piece of work.

90

95

100

105

6. In a rotary grinding machine, a turn-table, a stop lever controlling the operation of the turn-table and having a normal retracted position permitting rotation of the table, and a plurality of grinding units mounted on the table following one another around a common orbit and each consisting of a wheel, a work-holder and a wheel support having a raised position and a low position respectively for grinding and non-grinding by the wheel in combination with abutments on the individual supports each adapted to operatively engage or miss the stop lever at a definite point of the orbit of its unit, according as the support is then in its raised position or in its low position.

110

7. In a multiple grinding machine, a plurality of grinding units each consisting of a grinding wheel, a bearing support thereof, means for driving the wheel within its bearing support, a work-holder, and means for moving the bearing support in a direction axial of the wheel for applying the wheel to or removing it from contact with the work in the work-holder, means for progressing the grinding units along a path, lever means for starting and stopping the progression, and a bar moving vertically with the bear-
